UNITED STATES PATENT OFFICE

GEORGE W. HARVEY, OF MEDFORD, MASSACHUSETTS

DESIGN FOR A FISH LURE

Application filed February 20, 1933. Serial No. 47,267. Term of patent 3½ years.

To all whom it may concern:

Be it known that I, GEORGE W. HARVEY, a citizen of the United States, and a resident of Medford, in the county of Middlesex and State of Massachusetts, have invented a new, original, and ornamental Design for a Fish Lure, of which the following is a specification, reference being had to the accompanying drawing, forming part thereof.

Referring to the drawing,

Fig. 1 is a top plan view of a fish lure showing my new design; and

Fig. 2 is a side elevation of said fish lure.
I claim:

The ornamental design for a fish lure, substantially as shown.

In witness whereof I hereunto subscribe my name this 17th day of February, A. D. 1933.

GEORGE W. HARVEY.
